UNITED STATES PATENT OFFICE.

ERNEST DALTROFF, OF PARIS, FRANCE, ASSIGNOR TO CARON CORPORATION, OF NEW YORK, N. Y., A CORPORATION OF NEW YORK.

DESIGN FOR A BOTTLE.

Application filed February 4, 1929. Serial No. 29,903. Term of patent 14 years.

To all whom it may concern:

Be it known that I, ERNEST DALTROFF, a citizen of the Republic of France, residing at Paris, France, have invented a new, original, and ornamental Design for a Bottle, of which the following is a specification, reference being had to the accompanying drawing, forming a part thereof.

In the drawing:

Fig. 1 is a perspective view of a bottle showing my new design;

Fig. 2 is a top plan view thereof; and

Fig. 3 is a bottom plan view.

I claim:

The ornamental design for a bottle, as shown.

E. DALTROFF.
